United States Patent Office.

RUFUS M. EASTMAN, OF BOSTON, MASSACHUSETTS, ASSIGNOR TO
HIMSELF AND FRANCIS L. BOYD, OF SAME PLACE.

Letters Patent No. 92,291, dated July 6, 1869.

IMPROVED AUTOMATIC TONGS.

The Schedule referred to in these Letters Patent and making part of the same.

Be it known that I, RUFUS M. EASTMAN, of Boston, in the county of Suffolk, and State of Massachusetts, have invented a new and useful instrument, called "Eastman's Automatic Tongs," for handling objects beyond the reach of the arm, as goods or articles in shop-windows, or similar places; and I do hereby declare that the following is a full, clear, and exact description of the construction and operation of the same, reference being had to the annexed drawings, making a part of this specification, in which—

Figure 2 is a representation of the instrument, with the jaws closed; and

Figure 1, a representation of the same, partially opened.

The instrument may be made of wood, or other suitable material, and may be of any required size.

In fig. 1, the stationary part A forms, at one end, the lower jaw of the "tongs" *e*, the other end forming the handle *e*.

The movable part B, and the movable jaw *f*, are

both connected by the oscillating-hinge *H* to the stationary part A.

The parts A and B are also connected in such a manner, *i*, as to allow B to be drawn backward and forward horizontally by the thumb of the same hand that holds the instrument, thereby opening and closing the jaws.

It may also be provided with a spring for either opening or closing the jaws, thereby necessitating but one motion of the thumb when using.

What I claim as my invention, and desire to secure by Letters Patent, is—

The automatic tongs, composed of devices A, B, H, *f*, and *e*, combined and arranged substantially as specified.

RUFUS M. EASTMAN.
